US00D989972S

(12) **United States Design Patent** (10) **Patent No.:** **US D989,972 S**
Long (45) **Date of Patent:** **** Jun. 20, 2023**

- (54) **TRANSCUTANEOUS ELECTRICAL NERVE MUSCLE STIMULATION DEVICE**
- (71) Applicant: **Haifei Long**, Anhui (CN)
- (72) Inventor: **Haifei Long**, Anhui (CN)
- (**) Term: **15 Years**
- (21) Appl. No.: **29/797,808**
- (22) Filed: **Jul. 2, 2021**
- (51) LOC (14) Cl. **24-01**
- (52) U.S. Cl. **USPC D24/200**
- (58) **Field of Classification Search**

(57) **CLAIM**

The ornamental design for a transcutaneous electrical nerve muscle stimulation device, as shown and described.

DESCRIPTION

FIG. 1 is a perspective view of a transcutaneous electrical nerve muscle stimulation device showing my new design; FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is an enlarged top view thereof; and,

FIG. 8 is an enlarged bottom view thereof.
